STARTING AND REGULATING APPARATUS FOR
FREE-PISTON COMPRESSORS

Erich A. Wachsmuth, Michigan City, Ind.

Continuation of application Serial No. 285,472, May 1, 1952. This application January 2, 1957, Serial No. 634,395

4 Claims. (Cl. 230--9)

This invention relates to free-piston internal combustion engine-driven compressors, and more particularly to starting and regulating apparatus for such compressors.

Free-piston machines of the character referred to are usually started by compressed air. The engine-compressor piston pairs are moved to the outer ends of their strokes and locked in what may be called "starting position." They are then subjected to the pressure of an expansible fluid under pressure tending to force them together, and when that pressure is at the requisite level for starting, the pistons are released and driven towards each other by the expansion of the expansible fluid, and the air trapped between the motor pistons is compressed to such a degree that fuel injected into the motor cylinder in the neighborhood of the "dead center" is ignited, and the explosion drives the pistons apart again. By the end of this first stroke, there must, independent of the pressure in the receiver to which the compressor may be discharging (for that pressure might be low), be energy stored up sufficient to return the piston pairs to their inner positions and to compress the air between the engine pistons to the requisite degree. This is accomplished in various ways, as by interposing a pressure-maintaining valve between the discharge valves of the compressor and the receiver, thus causing the compressor, regardless of the prevailing receiver pressure, to work against a pressure which is at least equal to the lower limit of the rated pressure range, the motor-compressor, from the very first stroke, operating under the equivalent of full load by virtue of the pressure-maintaining valves located, in the path of flow of delivered air, ahead of the receiver. Another arrangement involves the provision of special accumulator, buffer or dash pot cylinders, independent of the compressor cylinders; and a combination of the two arrangements is a further possibility.

In my copending application, Serial No. 272,019, filed February 18, 1952, now Patent No. 2,775,398 for Free-Piston Compressor, a quite different starting arrangement is employed. There a twin unit is started by the explosion of a suitable powder charge producing a pressure acting between the motor pistons of one pair to force apart the piston pairs of which such motor pistons form a part. According to that arrangement, the pistons in the "starting cylinder" (the motor cylinder in which the explosion to effect starting is to take place) are brought close to each other—into their inner "dead center" positions, and driven apart by the ignition of a predetermined powder charge. Thereupon, through the coupling of the pistons which characterizes this design, a driving together of the piston pairs of the other cylinder takes place, and the air between the motor pistons of these latter pairs is compressed, and fuel injected near the dead center point of this latter cylinder is ignited, and the pistons of this cylinder are driven apart while compression is again effected in the first cylinder. The machine of application Serial No. 272,019, now Patent No. 2,775,398 also needs pressure-maintaining valves or buffer cylinders, but its need for them, in contrast with the free-piston machines

2

first described (which would not otherwise make a second stroke) is to prevent the machine from running away.

The general object of the present invention is to provide, without the necessity for pressure-maintaining valves or special buffer cylinders (which are undesirable both from the operating and the cost standpoint), an improved apparatus for the satisfactory and simplified starting of twin free-piston machines. Another object is to provide an improved starting and controlling apparatus for free-piston compressors of the type mentioned. A further object is to provide an improved method for the starting and control of free-piston machines. Still another object is to provide an improved controlling device for governing a free-piston machine while receiver pressure is below the lower designed working limit and, in association therewith, improved means automatically controlled while receiver pressure is between the relatively closely spaced upper and lower limits of the designed pressure range for controlling the air delivery of the machine and governing the fuel supply so that it is properly related to the air delivered. Yet a further object is to provide an improved controlling device for governing a free-piston machine including two pressure responsive control devices, the first, in control while the delivery pressure of the compressor is below the lower limit of the designed pressure range, acting to control the fuel supply to the motor, increasing it as the pressure against which the compressor discharges increases, and the other, in control while the compressor is delivering air at pressures between the upper and lower limits of its designed range, controlling the quantity of air delivered to maintain the receiver pressure within the desired range and taking over the control of the fuel supply to the motor and controlling the supply so as to maintain the power output and the work done by the compressor in balance. Other objects and advantages of the invention from its various aspects will hereinafter appear.

According to the invention, after the ignition of the powder starts the machine, and up to the time the lower limit of the designed pressure range of the compressor is reached, the quantity of fuel injected is automatically regulated to keep step with the continuously increasing work required for the compression of air to the progressively increasing discharge pressure and its discharge against such increasing pressure, but, as the receiver pressure varies in the range between the lower limit of the designed range and the upper designed limit, the quantity of compressed air discharged per stroke is varied while there is effected a concurrent change in the quantity of injected fuel quantity decreasing, between the lower and upper limits of the designed normal pressure range, from a quantity suited to full load operation to one suited to no load operation.

A very desirable embodiment of the apparatus aspect of the invention includes a pressure responsive device (a "starting" pressure responsive device) engaging, indirectly or directly a suitable transmission element—a two-armed lever is appropriate—and acting through the latter upon the regulating element of the fuel pump, in such a manner as to effect an increase in the quantity of fuel delivered with an increase in the pressure to which said pressure responsive device is subjected, the operating range of this mechanism lying between absolute atmospheric pressure (substantially zero gauge) and the lower limit of the designed operating range. This embodiment further includes a second pressure responsive device (an "operating" one), which is effective between the lower and upper limits of the designed pressure range of the apparatus—that is, within the normal operating range—and which acts, indirectly or directly, on the free end of the two-armed lever in such a manner that the quantity of fuel injected is diminished with increases in the pressure to which the second pressure responsive

device is subjected, and also acts upon the adjusting element of a device which controls the quantity of air delivered by the compressor (desirably controlling the quality of air within the compression spaces of the compressor upon the commencement of compression) in such a way that the delivered air is varied between a maximum and zero directly as the quantity of fuel is varied.

Regulation of fuel quantity in accordance with the work of compression may be effected through the use of pumps with inclined (sloping) control edges. If the control edge is appropriately shaped, pump output can be controlled by imparting to the plunger rotation on its axis which is a straight line function of the receiver pressure, but this necessitates the employment of abnormal (specially end-contoured) pump plungers. If it be desired to employ normal pump plungers with an inclined control edge of linear pitch, this is possible by determining, through calculation or empirically, the requisite form of a variable displacement device, and interposing the latter in the transmission between the "starting" pressure responsive device and the regulating rod which the latter controls. Further, for the designed range of operating pressure, the work of compression is to be adjusted to the quantity of fuel injected as that quantity is determined by the receiver pressure, through a suitable formation of the control edges on the apparatus (shortly to be explained) which regulates the air output. This latter apparatus may be a hydraulic impulse-producer similar to the fuel pump, and, like the fuel pump, have an inclined-edge control, and, in accordance with the momentary setting of its adjusting element, hydraulically control claws or fingers acting on the compressor inlet valves in such a way that these valves are kept open over a shorter or longer portion of the compression stroke.

In the accompanying drawings in which, for purposes of illustration, two illustrative embodiments and certain modifications of the invention are shown,

Fig. 1 is a somewhat diagrammatic view, in central longitudinal section and with parts in elevation, through a twin motor-compressor in which the illustrative embodiments of the control apparatus may be viewed as incorporated.

Fig. 2 is a transverse section on the line 2-2 of Fig. 1.

Fig. 3 is a diagrammatic view illustrating one form of automatic control apparatus.

Fig. 4 is a diagrammatic view illustrating another form of control apparatus.

Fig. 5 is a fragmentary detail sectional view showing portions of one possible constituent control apparatus.

Fig. 6 is a fragmentary detail sectional view showing elements of another possible constituent control apparatus.

Fig. 7 is an enlarged fragmentary view, partially in section, showing a detail of the apparatus of Fig. 5.

Figs. 8 and 9 are diagrams showing relations between pressures, strokes, valve lift, and claw or finger lift.

It will be understood that the control method and apparatus of this invention may be carried out in combination with various forms of free-piston compressors; but, for the purpose of rendering its explanation more readily comprehended, there is being illustrated in Figs. 1 and 2 a motor-compressor generally similar (but with some more detail) to one of the forms illustrated (the second form) in my application Serial No. 272,019, filed February 18, 1952, now Patent No. 2,775,398, for Free-Piston Compressor. The somewhat more diagrammatically illustrated apparatus of the first form of that application might equally well be employed.

Now, referring first to Figs. 1 and 2, it will be noted that the motor-compressor comprises, as shown, twin motor-cylinders 1, 1' which have their axes at least substantially parallel and which are supported by a frame F. In the motor-cylinders 1, 1', there are reciprocable, in

counterstroke relation to each other, pistons 4, 5 and 4', 5' which control scavenging slots 2 and exhaust slots 3. These four pistons, formed as differential pistons, are coupled in pairs (4 with 4' and 5 with 5'), each pair by a double-armed rocker 6, 7 (otherwise stated: centrally pivoted levers), the first pair by the rocker 6 and the second by the rocker 7, so that the outward travel (working stroke) of the pistons associated with the cylinder 1, occurs with (indeed compels) the inward (compression) stroke of the corresponding pistons in the cylinder 1' and vice versa. The two double-armed rockers 6 and 7 are pivoted respectively by shafts 8 and 9 in the frame F, and they have in fixed relation to them two gear segments 10 and 11 which swing in the same directions as their respective rockers, and these two segments, through their mutual engagement, prevent the piston systems from getting out of synchronism with each other. The outer ends of the double-armed rockers 6 and 7 are designated 21 and 22. The outer ends of each arm are provided with bearings 24 surrounding pins 25 which are in turn supported in box elements 26, and these box elements are slidably arranged in guides 27 extending transversely to the several pistons and providing for guided movement of the box elements 26 transversely of the pistons as the latter reciprocate.

Compressor cylinders 32 and 33 and 32' and 33' are disposed coaxially with the motor-cylinders 1, 1', and are open at their ends toward the engine cylinders, but closed at their outer ends by cylinder heads 34, 35 and 34', 35' which carry the suction and discharge valves 36 and 37. Two receivers 38 are shown, to which pistons 39, 40, and 39', 40' pump fluid. Twin fuel injection pumps, indicated diagrammatically in Figs. 3 and 4, may be driven, as from the rocker shaft 9, in any suitable manner.

To start the compressor, the pistons 4, 5, for example, may be brought in any suitable manner to their mutually adjacent "dead center" positions. A small cartridge, provided with a small powder charge, is inserted in a suitable chamber C communicating with the space D between the pistons 4, 5 of the motor-cylinder 1, and, when this powder charge is ignited in any suitable manner, the pistons are forced apart in cylinder 1, and compression is effected in the cylinder 1' so that the injection of fuel, as the pistons 4', 5' approach each other, will result in an explosion occurring in cylinder 1' forcing the pistons 4' and 5' apart again. When the piston 4, 5 overrun the exhaust and scavenging slots 3, 2 in the starting cylinder 1, that cylinder is scavenged and charged as during normal operation, and simultaneously the normal charge of combustible mixture is injected into the counter cylinder 1', in which compression has been caused to take place by the motion transmitted by the rockers; and, upon the ignition of this mixture, running will be continued under the control of the apparatus which will now be described.

The internal combustion engine cylinders 1 and 1' are adapted to have fuel supplied to them by a two-cylinder fuel injection pump P, which is shown diagrammatically in each of Figs. 3 and 4. The construction of this pump need not be illustrated as it may be of conventional form and has the quantity of fuel which it delivers varied in a well-known manner, as by the reciprocation of a rack bar R, which rotates the pump plungers on their axes in such a manner as to vary the fuel delivery of the pump between a maximum and zero. It will be appreciated that by the proper shaping of the usual slanting control edge of the pump plunger, practically any desired rate of fuel delivery can be effected as a function of the angle of rotation of the piston. In the diagrammatic arrangement illustrated in Fig. 3, the rack bar R is displaced as a function of the receiver gauge pressure under the control of a pressure responsive device 41. When this is done the control edge of the pump plunger will be so formed that the movements of the rack bar R are co-

ordinated with receiver pressure in such a manner that when receiver pressure is one atmosphere gauge there is supplied the proper quantity of fuel to be burned to effect the compression and discharge of the quantity of air taken in, and when receiver pressure is two atmospheres gauge, the quantity of fuel injected is modified to provide the work involved in delivering against a pressure two atmospheres the air taken in, etc.

A systematic calculation, on the assumption of normal partial load efficiencies of the motor and on the basis of output increments measured on single stage compressors, demonstrated that between one and eight atmospheres receiver pressure (roughly zero and 103 pounds gauge), the amount of fuel required to be injected increased linearly with the air pressure. Accordingly, when a closed fuel pressure system is used, it should be possible to use a fuel pump with a helix-shaped control edge in a system such as is diagrammatically shown in Fig. 4, with the angle of inclination of the helix determined from the maximum useful stroke, the maximum and minimum delivery, and the fuel pump plunger displacement angle (degrees of rotation on its axis) between full load and no load. Deviations resulting in actual practice between the delivery law of the plunger thus determined, for example, of the pump and the actual fuel requirement may be taken care of by the insertion of a variable displacement device 68 to correct the movement of the regulating rod as shown in Fig. 4. The pressure responsive device 41 maintains control of the fuel injection pump between zero (standard atmospheric pressure at sea level) pressure and the pressure which is selected in the design of the apparatus as the lower limit of the desired normal operating range, and as the design features which have been described are generally well-known in the internal combustion engine art, it is unnecessary to illustrate any of the details of construction of the fuel pump. It may be said, however, that there may be employed any suitable conventional fuel pumps, including pumps similar to the hydraulic impulse givers later described, such pumps having cam-actuated plungers provided with generally helically disposed surfaces and rotatable on their axes to vary the fuel delivered, said surfaces, through their uncovering or covering, according to their disposition on the plungers, of a lateral port extending between the pump cylinder bore and a fuel supply space, determining the end or the beginning of fuel delivery. These pumps may, for example, be actuated from the shaft 9; and, if fuel injection during any portions of the working strokes were desired, accumulators might be provided as needed.

Another pressure responsive device, responsive to receiver pressure, is shown at 43 and this controls a device 42 for controlling the quantity of air delivered, and this pressure responsive device 43 becomes operative as a control as soon as receiver pressure exceeds the normal lower limit of the operating range, for example seven atmospheres gauge. Within the normal operating range from, say, 7 atmospheres gauge to 7.7 atmospheres gauge, the device 42 adjusts the amount of air delivered by the compressor from maximum all the way down to zero delivery. In accordance with the two compressor systems operating in counterstroke relation, device 42 consists of two congruent units which, like the fuel pumps, are suitably arranged in opposed relation and are driven in opposite directions by the symmetrical flanks of a cam located on a free shaft end (herein an end of shaft 3) of the rocker whose shaft does not actuate the fuel pump. As in the case of the fuel pump, the control element of each unit is a plunger with a sloping control edge reciprocated in rhythm with the motor-compressor piston with which it is coordinated and moving in a bore in a cylinder which is provided for it. The shape of the control edge is determined empirically, in connection with the mechanical coupling for the control rod of the fuel pump, so that for each load stage of the

compressor the work output of the motor and the work absorbed by the compressor are in equilibrium.

During each reciprocation of its piston the control device 42 produces in a well-known manner pressure impulses which are used to control claws or fingers cooperating with the compressor suction (inlet) valves in such a way that the suction valves are held open for a smaller or larger portion of the compression strokes. Each of these control units acts simultaneously on two claw or finger systems, one associated with each of the aligned compressor cylinders of a pair.

Two different control arrangements for maintaining the inlet valves open for the desired portions of the compression strokes of the compressor pistons are shown respectively in Figs. 5 and 6. In the arrangement of Fig. 5 the control unit consists of an edge-controlled pump 45 with suction valve 46, but without discharge valve. The figure shows the controlling piston or plunger 51 in its lower dead position. With respect to the compressor, this position corresponds to the dead position preceding the compression stroke, in other words the positions occupied by the pistons in the compressor cylinders 32, 33 in Fig. 1 of the drawings. It will be understood that, since, when a reciprocating element reverses its motion, it is stationary for an instant between its opposite strokes, it has a "dead position" or "dead point," and indeed such "dead positions" and "dead points" occur at each of the opposite ends of the paths of reciprocation. Commonly the "dead points" and "dead positions" are known as "dead center" positions when the reciprocating element is connected by a connecting rod with a crank, and it is believed no unwarranted extension of usage of the term "dead center" to apply it to a free-piston type of machine to indicate the ends of the piston strokes.

When the piston or plunger 51 goes up, immediately the pressure medium (e. g. oil) filling the space 53 is pushed out, against the spring force opposing movement of the claws or fingers 60, into the cylinders 61, until the claw- or finger-operating pistons 62 are stopped by the abutment 63. Thereafter the pressure medium displaced by the plunger is blown off through a closed fuel injecting nozzle 70 connected back to the fluid supply and acting as a safety valve whose relief pressure is higher than the pressure reached in the system at the moment the claw-operating piston is stopped by its abutment. As the oblique edge S moves (upwards in Fig. 5) over the control port 52, the pressure in the system is relieved, and the claw spring 64 pushes the claw piston 62 and claws back into the inoperative position with high acceleration. At this instant only can the compressor suction valve close and the compression begin (see diagram of Fig. 8). The control piston or plunger 51, continuing its upward movement, now expels the pressure medium from the space 53 above the piston through the laterally vented central bore 54 in the piston and the control port 52 into the space 55, which communicates with the suction space 57 through the throttle gap 56. When the plunger 51 moves down, the suction valve 46 opens, so that pressure medium can flow from the suction space 57 into the developing space 53, during the entire downward movement of the piston, and an evacuation of the system, with vacuum formation, is reliably prevented.

The pressure impulses produced by the above described control arrangement give a control which is not symmetrical with respect to the dead position. The fact that delivery of pressure medium, which here sets in positively only with the piston reversal of the motor-compressor (see Fig. 8) is the reason the control impulse arrives at the claws a little (though only a little) after the piston reversal and why the claws start to move in a direction to maintain the compressor suction valves open only after the compression stroke has set in, geometrically speaking. In view of the fact that suction valves, as a result of their inertia, close late too, this re-

7 tardation will as a practical matter have no serious disturbing effect on the regulation.

The specific control arrangement of Fig. 6 may now be noted. With fundamentally the same arrangement as in Fig. 5, but with modified control cam position, modified plunger 51' with modified control edge S', and with replacement of the "safety valve" 70 (Fig. 5), by a preloaded pressure medium accumulator 80, a control operating symmetrically with respect to the dead point can be effected (see Fig. 9). It is also possible to do without the suction valve 46 of Fig. 5. The outward movement of the piston 51' is coordinated in this arrangement with the suction stroke of the compressor. In other words, the upward movement of this plunger occurs during the suction strokes of the compressor pistons, and not, as in Fig. 5, during their discharge strokes. The oblique control edge S' of the piston 51' determines the beginning of delivery. The upwardly moving piston at first forces the control medium from space 53 back into the suction space 57. When the control port 52 is covered—earlier or later depending on the amount of plunger rotation—by the slanting edge S', fluid delivery commences and the claw-operating piston is displaced against spring force in the "keep open" direction at a velocity which corresponds to the reduced plunger velocity. After the claw-operating piston 62 is stopped by abutment 63, the control medium delivered is stored by the pressure medium storage tank or accumulator 80. Delivery and storage continue until reversal of the plunger 51'. Upon reversal, the system remains under the storage pressure until the accumulator 80 is empty. Only then does the claw piston 62 go back under the pressure of the spring 64 acting on it. It reaches its inoperative position at the moment the control edge S' reopens the control port 52. The plunger 51' itself continues to move while the space 53 being created by its movement fills up from the suction space 57 until the lower dead position is reached.

The arrangement of Fig. 6 ensures a correctly timed control also in the partial load range close to full load, because the claw movement occurs symmetrically to the dead point, that is, it sets in at any rate before the dead point. The relatively slow return of the claw piston must be compensated for by a corresponding setting of the instant of control. This arrangement presupposes a tight pressure medium storage system for the claw control. Leakages would displace the instant of claw return toward full load. Since as to fuel supply no correction in the same sense takes place, major system leaks would disturb the equilibrium between motor and compressor and the machine would come to a standstill.

In each of the arrangements of Figs. 5 and 6 the hydraulic impulse givers have their plungers actuated as shown by cams 100 (Fig. 5) and 100' (Fig. 6) mounted on the rocker shaft 8, but by reason of the different dispositions of the cams and the different formations of the plungers 51 and 51', projection of the claws or fingers commences immediately after the commencement of the compression strokes of the compressor pistons in the arrangement of Fig. 5, but commences in Fig. 6 after the suction stroke is well under way and before the pistons 39 and 40 reach the positions of Fig. 1. The controlling rod R' (rack bar) for rotating the plunger 51 or 51' is shown in both Fig. 5 and Fig. 6.

With this detailed description of component structures, it is possible to return advantageously to Figs. 3 and 4.

Either the arrangement of Fig. 5 or that of Fig. 6 may be employed in either of the schematically shown arrangements of Figs. 3 and 4.

According to schematic Fig. 3 the adjustment of the fuel supply to the work of compression and discharge of the air (which is dependent on the receiver pressure), and of the quantity of air to be handled to the fuel supplied, are obtained by giving a suitable form to the fuel-pump

8 control-edges and to the control-edges of the device 42 controlling the quantity of air delivered.

In detail: 41 represents the pressure responsive device (starting box), acting between 1 atm abs and the lower limit of the designed pressure range, and consisting of a cylinder 82, a piston 83 with a piston rod 84 and a spring 85. 86 represents the point of pivotal connection of the piston rod 84 with a two-armed lever 87, which is connected, on the one hand, with the regulating-rack R of the fuel pump P, and, on the other hand, at the articulation point 90, with the displacing element (regulating rod) R' of the device 42 controlling the quantity of air pumped by the compressor. The pressure responsive device (operating box) 43, acting over the pressure range between the lower and the upper designed operating pressures consists of the cylinder 94, the piston 95 with its piston rod 96 and the spring 97 suitably tensioned to cause it to commence to yield only when the lower rated pressure is exceeded. (It may be made responsive to the excess of receiver pressure over a predetermined pressure, by the use of a suitable relief valve permitting only the excess to pass it.) Due to the high spring tension and the relatively small effective pressure, the active range of this device is but small. It transmits, via the lever 88 acting on the control element R', adjustments to the regulating-rod R necessary for the regulating between zero- and full-load. 89 and 89' are pressure lines connecting the pressure boxes (pressure responsive devices) 41 and 43 with the receiver (not shown in Fig. 3). It will be understood that with twin pumps and twin hydraulic impulse givers the elements R and R' will be duplicated and those of each pair will be concurrently actuated.

Fig. 4 shows fundamentally the same arrangement, although under the employment of a normal fuel pump, that is, a pump with a linear control-edge pitch. In this the regulating-control-rod path and the receiver pressure can no longer be truly proportional with each other. Here the transmission of the action of the pressure box 41' to the regulating rod R of the fuel pump takes place through an interposed motion adjusting plate 68, which, on being rotated, as by a rack and pinion transmission 91, by the piston 83 of the pressure box 41', controls the displacement of the positively-connected motion adjusting plate 63, and this determines the path of the rod 84. Note plate 68 controls position in both directions.

The method of operation of the arrangements of Figs. 3 and 4 is, for the rest, exactly alike.

The illustrations correspond to the conditions present before starting of the compressor. With rising receiver pressure the pistons 83 move, against the pressure of the springs 85, toward the right, while the pistons 95, owing to a high spring tension, remain at first at rest. The pistons 83, moving toward the right displace, through the lever 87 swinging about the stationary point 90, the regulating rod R, in accordance with the increasing work of compression, toward full load, which is reached at the end position of the pistons 83, corresponding to the lower limit of the designed normal pressure range. As the pressure continues to rise further, the pistons 95 commence to move toward the right, and to displace, through the adjusting element R', which is also moving toward the right, that is, in the direction of zero delivery, and through the lever 87, which is now swinging about the now stationary point 86 the regulating rod R of the fuel pump toward the left, that is, toward no-load running.

The starting- and regulating-method and apparatus according to the invention has been developed for twin free-piston machines. However, it is not limited to the latter, but is also applicable to free-piston machines of conventional construction, provided it is possible to start the latter at no-load. This is fundamentally possible with machines operating with a buffer cylinder of their own, provided that their design is such that the total energy necessary for motor piston return and the work of com-

pression-work can be stored in the buffer cylinder without the help of the compressor cylinder.

In conclusion, the diagrams of Figs. 8 and 9 may be noted briefly. These may be regarded as illustrative of the use of the inlet valve controls of Figs. 5 and 6 respectively. In Fig. 8, it will be noted that the inlet valve opens at the end of the reexpansion of the air in the clearance spaces of the compressor and remains open throughout the rest of the suction stroke. They start to reseat at the end of the suction stroke, but are held open for a part of the discharge stroke by the claws or fingers, which are actuated right after the compression stroke commences, and are held in valve opening position until the edge S overruns the port 52 and lets the pressure acting on the plunger 62 bleed down.

In Fig. 6, the cam 100' commences to move the plunger 51' at the beginning of the suction stroke, but no fluid is displaced which moves the plungers 62 until the edge S' closes the port 52. This, as illustrated in Fig. 9, occurs at about $\frac{3}{4}$ stroke, but it may obviously occur later or earlier dependent on the rotation of the plunger 51'. The claws then move out and at the end of the suction stroke will prevent the closure of the inlet valves which had been opened and were held open by suction. During the discharge stroke the plunger 51' will be permitted to move down and uncover the port 52, the inlet valves will close, and compression of fluid will commence, the amount discharged depending on how late in the discharge stroke the inlet valves are held open.

This application is a continuation of my copending application Serial No. 285,472, filed May 1, 1952 now abandoned.

While there are in this application specifically described two forms and certain modifications which the invention may assume in practice, it will be understood that these are shown for purposes of illustration, and that the invention may be modified and embodied in various other forms without departing from its spirit or the scope of the appended claims.

What I claim is:

1. In an apparatus for varying the quantity of fluid delivered per stroke by a compressor which includes a reciprocable piston, a cylinder for said piston, said cylinder and piston coacting to form a chamber in which compression of a fluid is effected by relative movement between said cylinder and piston, said cylinder having an inlet valve, a shaft and a connection between said shaft and piston such that they move in given relation to each other, in combination, hydraulically operable expandable chamber mechanism for holding the inlet valve open through a portion of the compression stroke of the piston, a hydraulic impulse giver having means for varying the period during which it displaces fluid, means driven by said shaft for causing said impulse giver to start to deliver its impulse with the compression stroke of said piston, conduit means connecting said impulse giver with said hydraulically operable expandable chamber mechanism whereby impulses delivered by the former control the operation of the latter, and means governed by compressor discharge pressure controlling said hydraulic impulse giver to adjust the period during which the expandable chamber mechanism is subject to the impulse.

2. In an apparatus for varying the quantity of fluid delivered per stroke by a compressor which includes a reciprocable piston, a cylinder for said piston, said cylinder

and piston coacting to form a chamber in which compression of a fluid is effected by relative movement between said cylinder and piston, said cylinder having an inlet valve, a shaft and a connection between said shaft and piston such that they move together, in combination, hydraulically operable expandable chamber mechanism for holding the inlet valve open through a portion of the compression stroke of the piston, a hydraulic impulse giver having a plunger initiating an impulse upon attaining a given position and having means for varying the period during which it delivers its impulse, means turning with said shaft for causing said impulse giver to start to deliver its impulse with the compression stroke of said piston, conduit means connecting said impulse giver with said hydraulically operable expandable chamber mechanism whereby impulses delivered by the former control the operation of the latter, and means governed by compressor discharge pressure for adjusting said means for varying the period of delivery of the impulse by said impulse giver to vary such period.

3. In an apparatus for varying the quantity of fluid delivered per stroke by a compressor which includes a reciprocable piston, a cylinder for said piston, said cylinder and piston coacting to form a chamber in which compression of a fluid is effected by relative movement between said cylinder and piston, said cylinder having an inlet valve, a shaft and a connection between said shaft and piston such that they move in given relation to each other, in combination, hydraulically operable expandable chamber mechanism for holding the inlet valve open through a portion of the compression stroke of the piston, a hydraulic impulse giver having a reciprocable plunger and means for varying the duration, from a constant point in its stroke, of its displacement of fluid, means for initiating plunger movement at the commencement of the compression stroke of said piston, means connecting said impulse giver with said hydraulically operable expandable chamber mechanism whereby impulses delivered by the former control the operation of the latter, and means governed by compressor discharge pressure for adjusting said duration-varying means for varying the period of delivery of the impulse by said impulse giver.

4. In an apparatus for varying the quantity of fluid delivered per stroke by a compressor which includes a reciprocable piston, a cylinder for said piston, said cylinder and piston coacting to form a chamber in which compression of a fluid is effected by relative movement between said cylinder and piston, said cylinder having an inlet valve, a shaft and a connection between said shaft and piston such that they move in synchronism, in combination, hydraulically operable expandable chamber mechanism for holding the inlet valve open through a portion of the compression stroke of the piston, a hydraulic impulse giver having means for varying the period during which it displaces fluid, means driven by said shaft for causing said impulse giver to deliver its impulse during the compression stroke of said piston, conduit means connecting said impulse giver with said hydraulically operable expandable chamber mechanism whereby impulses delivered by the former control the operation of the latter, and means governed by compressor discharge pressure for adjusting said means for varying the period of fluid displacement by said impulse giver to vary such period.
